CLAIM

The ornamental design for faucet handle assembly, as shown and described.

DESCRIPTION

FIG. 1 is a front view of our new design of a handle assembly, a rear view thereof being a mirror image of the front view;

FIG. 2 is a top view of our new design of the handle assembly;

FIG. 3 is a bottom view of our new design of the handle assembly;

FIG. 4 is a left side view of our new design of the handle assembly;

FIG. 5 is a right side view of our new design of the handle assembly; and,

FIG. 6 is a perspective view of our new design of the handle assembly.

1 Claim, 2 Drawing Sheets
